UNITED STATES PATENT OFFICE.

CHARLES WINTER, OF WOODBURY, NEW JERSEY, ASSIGNOR TO STAR SEAL COMPANY,
A CORPORATION OF NEW YORK.

SEAL-FEED FOR BOTTLE-CAPPING MACHINES.

1,140,090.

Specification of Letters Patent. Patented May 18, 1915.

Application filed May 25, 1909, Serial No. 498,282. Renewed October 17, 1914. Serial No. 867,242.

To all whom it may concern:

Be it known that I, CHARLES WINTER, a citizen of the United States, residing at Woodbury, county of Gloucester, State of New Jersey, have invented certain new and useful Improvements in Seal-Feeds for Bottle-Capping Machines, of which the following is a specification.

My invention relates to mechanisms for automatically separating bottle seals from a mass and feeding them one at a time into the sealing head of a machine for applying them to bottles, so that on each down stroke of the sealing head it is provided with a seal.

My separating and feeding mechanism may be used whether the bottles are fed automatically or by hand, as the feeding of the seals to the head is dependent upon and controlled by the reciprocation of the sealing head whether that head is reciprocated continuously or intermittently.

My invention is particularly adapted for separating and feeding seals such as shown in my Patent No. 904,825, of November 24, 1908, but I do not wish to be understood as limiting myself to use with this particular seal, as my invention may be used with any seal having lugs or tongues.

I accomplish the separation by providing an opening having one or both of its bounding surfaces small enough to enter the space between the tongues of the seal, said opening being so narrow that a single seal cannot pass through except by rolling around the narrow edge, as will hereafter appear. By this arrangement a seal can pass through in one position only, and only one seal can pass through at a time.

Referring to the drawings, Figure 1 is a side elevation, partly in section, of the upper part of a seal applying machine provided with my improved separating and feeding mechanism; Fig. 2 is a rear elevation thereof; Fig. 3 is a horizontal section on an enlarged scale, taken on the line III—III of Fig. 1; Fig. 4 is a section on the line IV—IV of Fig. 3; Fig. 5 is the same view as Fig. 4 with the parts in different positions; Fig. 6 is a detail section on the line VI—VI of Fig. 4; and Figs. 7 and 8 are enlarged details showing the manner in which the seal passes through the opening of the separator.

1 is the upper part of the main frame of a 55 bottle capping machine, below which are the well known mechanical devices for reciprocating the sealing head.

2 is the reciprocating rod carrying the sealing head 3, which I have indicated as being of the construction shown in my co-pending application Serial No. 469,963, although any form of sealing head may be used.

From the main frame 1 extends a bracket 65 4, in which is rigidly mounted a supporting column 5, on the top of which is secured the frame or yoke 6 which carries the hopper and separating drum.

Keyed in the yoke or frame 6 is a shaft 70 7, on which shaft is journaled a hollow drum 8. To the end of this hollow drum there is secured a ratchet wheel 9, and adjacent thereto there is journaled on the shaft a rock arm 10 carrying the pawl 11. The 75 rock arm 10 is connected to the reciprocating sealing head by a link or rod 12, so that every time the sealing head reciprocates, the drum 8 is rotated slightly by the pawl and ratchet mechanism.

The drum 8 may be provided with a door 13 to permit access to and inspection of the interior, but ordinarily the said door may be closed by a spring or lock 14. The outer edge or rim 15 of the drum is rounded and 85 is provided with a flange 16. The outer or large end of the drum is closed by a plate 17, having a flange 18 which forms a gutter or channel 19 around the edge of the drum. The plate 17 is rigidly secured to the shaft 90 7, and the flange 16 of the drum 8 makes sliding contact with the flange 18 of said plate 17. The plate 17 has a large opening 20, over which is secured a hopper 21, into which the seals may be fed in quantities so 95 as to pass into the separating drum.

In the bottom of the flange 18 of the plate 17 is an opening 22, through which the seals may pass into a run-way 23.

I have now described that portion of my 100 invention which separates the seals and positions them ready for feeding, and I will now describe the operation of these parts with particular reference to Figs. 1, 7 and 8.

The seals are thrown indiscriminately in 105 quantities into the hopper 21, from which they pass through the opening 20 into the interior of the drum 8. Here the seals are

agitated by the step by step revolution of the drum due to the ratchet mechanism, so that the seals which are nested or stuck together are loosened and separated one from another. Owing to the taper of the drum, the seals slide down to the bottom of the edge 15 of the drum, the rounded portion of said edge being narrow enough to pass between the tongues of the seal 24. Furthermore, the distance between the plate 17 and the rim 15 of the drum is such that a seal cannot pass through unless it is in the position whereby the tongues first drop down over the edge 15, and then the seal continuing its movement rolls around said edge. This is clearly seen from Figs. 7 and 8, in which the seal is shown, first, rolling around the edge 15, and second, in a position in which it cannot pass through the opening.

After a seal has rolled around the rim 15, it drops down into the gutter 19, as shown in Fig. 1. Inasmuch as the rim 15 and the gutter 19 are continuous, several seals can drop through at different points at the same time, but all fall into the gutter in the same position and roll down to the outlet 22, where they fall one at a time into the run-way 23. If the run-way 23 is filled, the seals simply back up in the gutter 19, and as the seals are free to roll in said gutter, there is no danger of clogging. In practice the run-way 23 may be made long enough to hold quite a number of seals, so that it makes no difference whether several seals come through at one time or several reciprocations of the sealing head take place without a seal passing through. In other words, I utilize this mechanism for separating the seals but not for timing them in accordance with the strokes of the sealing head.

Having the seals thus separated and arranged in the desired position in the run-way 23, I drop them out of said run-way one at a time by means of a double stop at the lower end of the run-way. This double stop consists of a lever 25 journaled in a bracket 26 rigidly secured to the outside of the run-way 23. The run-way 23 has an opening 27 throughout its length, and the lower end of the lever 25 carries a stop 28, which passes into the run-way through the opening 27. Normally this stop 28 holds up all of the seals in the run-way. At the other end of the lever 25 is carried a spring pusher 29, which normally does not enter the opening in the run-way. The sealing head 3 carries a rod 30 which strikes a finger 31 on the lever 25 when the sealing head nears the upper limit of its movement. This rocks the lever 25 so that the stop 28 is drawn out from under the column of seals, and at the same time the spring pusher 29 pushes against the second seal in the column and temporarily supports the column so as to allow the bot-

tom seal to drop out. As soon as the sealing head starts down again, the stop 28 passes into its normal position, and the pusher 29 releases the column of seals, which drop down ready for another operation. The bottom seal in dropping out of the run-way, as just described, would probably slide into position in the sealing head, but as it might sometimes stick or catch, I prefer to make the feed certain by positively inserting the seal into the head by means which I will now describe, with particular reference to Figs. 3, 4, 5 and 6.

Rigidly mounted on the reciprocating sealing head is a horizontal trough-like member 32, having an opening in one side to receive the seal from the lower end of the run-way 23. Secured within the member 32 is a seal stop or guide 33, against which the seal rests after it slides into place from the run-way 23. The lower end of the run-way 23 is curved, as at 34, so as to bring the seal around and guide it into the trough of the member 32. Within the trough and back of the seal stop 33 is a slotted block 35, having therethrough a fixed pin 36. Integral with or rigidly attached to the forward end of the block 35 is a plate 37. A plate 38 is rigidly secured to the frame of the machine, and has therein a diagonal slot 39, in which the pin 36 travels.

The result of this construction is that the member 32 and its parts just described reciprocate up and down with the sealing head, while the plate 38 is stationary, and consequently the block 35 and its plate 37 reciprocate back and forth in the trough in time with the sealing head because of the motion of the pin 36 in the diagonal slot 39. Consequently, when the sealing head is at the upper end of its stroke, the opening in the trough of member 32 registers with the curved end 34 of the run-way 23, and the seal, which is at this instant released from the run-way by the withdrawal of the stop 28, drops into the trough on top of the plate 37, which at this time is at the forward end of its stroke.

Now as the sealing head descends, the pin 36, traveling rearwardly in the slot 39, draws back the block 35 and the plate 37 on which the seal 24 is resting. Rearward movement of the seal, however, is prevented by the seal stop 33, so that when the plate 37 reaches the limit of its back movement, or, in other words, when the sealing head is at the bottom of its stroke, the seal 24 drops off the plate 37 on to the bottom of the trough of the member 32. The position of the parts and the seal at this stage of the operation is shown in Fig. 5. Now as the sealing head starts up, the plate 37 moves forward, pushing the seal before it and into the sealing head through the opening 40, where it is grasped by spring fingers or any well known

form of chuck, which need not be here illustrated or described. Just as this seal is being pushed into its final position in the chuck, another seal is released by the rod

5 30 striking the finger 31, and a new seal drops into the position shown in Fig. 4.

It will be observed that I first individualize and position the seals without respect to the number so acted upon at each stroke of 10 the sealing head, and that I then release one of the positioned seals at each stroke of the sealing head and positively insert it into the seal chuck or catch in the sealing head.

Many modifications of the mechanical 15 details of the mechanisms which I have shown for carrying out these operations will occur to a mechanic skilled in this art, and I do not wish to be understood as limiting myself to the precise form of the apparatus 20 herein shown and described.

Having described my invention, what I claim is:

1. An apparatus for feeding seals of the character described to a bottle sealing device, comprising a receptacle for the mass 25 of seals, a chute communicating with said receptacle of a width to comfortably convey the seals only in endwise positions, and an entrance to said chute having an obstruction 30 to said seals making the width of the chute at that point less than the height of the seals, and enlarged parts above and below said obstruction to receive respectively the upper and lower tongues directed thereto of 35 endwise positioned seals to permit said positioned seals to rock around said obstruction to pass said tongues thereby in tilted positions.

2. An apparatus for feeding seals of the 40 character described to a bottle sealing device, comprising a receptacle for the mass of seals, a chute communicating with said receptacle of a width to comfortably convey the seals only in endwise positions, an entrance to said chute having an obstruction 45 to said seals making the width of the chute at that point less than the height of the seals, and enlarged parts above and below said obstruction to engage respectively the upper and lower tongues directed thereto of 50 endwise positioned seals to permit said positioned seals to worm around said obstruction to pass said tongues thereby in tilted positions, and means for agitating said mass of 55 seals at said entrance.

3. An apparatus for feeding seals of the 60 character described to a bottle sealing device comprising a receptacle for the mass of seals, a chute communicating with said receptacle of a width to comfortably convey the seals only in endwise positions, a contracted entrance to said chute making the width of the chute at that point less than 65 the height of the seals, said entrance having a zig-zag side wall to permit endwise

positioned seals having tongues directed toward said wall to worm their way past said zig-zag wall to carry their tongues past said contracted entrance in tilted positions.

4. An apparatus for feeding seals of the 70 character described to a bottle sealing device comprising a receptacle for the mass of seals, a chute communicating with said receptacle of a width to comfortably convey the seals only in endwise positions, a contracted entrance to said chute with a side face having an upper part flaring upwardly 75 away from said chute, a second part below and adjacent said contracted entrance flaring downwardly away from said chute and another part below and adjacent said second part flaring downwardly to said chute forming a zig-zag entrance to permit endwise positioned seals having flanges directed toward said zig-zag entrance having a tumbling motion to pass the said contracted entrance in tilted positions.

5. An apparatus for feeding seals of the character described to a bottle sealing device comprising a receptacle for the mass 90 of seals, a chute communicating with said receptacle of a width to comfortably convey the seals only in endwise positions, a contracted entrance to said chute with a side face having an upper part flaring upwardly 95 away from the said chute, an adjacent lower part flaring downwardly away from said chute and a part below and adjacent said last part flaring downwardly to said chute forming a zig-zag entrance to permit edge- 100 wise positioned seals having flanges directed toward said zig-zag entrance having a tumbling motion to pass the said contracted entrance in tilted positions, and means for moving said upper part.

6. An apparatus for feeding seals of the character described to a bottle sealing device comprising a receptacle for the mass of seals, a chute communicating with said receptacle of a width to comfortably convey 110 the seals only in endwise positions, and a contracted annular entrance to said chute making the width of the chute at that point less than the height of the seals, said entrance having an annular side wall of zig-zag formation to permit endwise positioned seals having flanges directed toward said zig-zag wall having a tumbling motion to pass the said contracted entrance in tilted 115 positions.

7. An apparatus for feeding seals of the character described to a bottle sealing device comprising a receptacle for the mass of seals, a chute communicating with said receptacle of a width to comfortably convey 125 the seals only in endwise positions, a contracted annular entrance to said chute making the width of the chute at that point less than the height of the seals, said entrance having an annular side wall of zig-zag for- 130

mation to permit edgewise positioned seals having flanges directed toward said zig-zag wall having a tumbling motion to pass said contracted entrance in tilted positions, and escapement mechanism passing a seal to the sealing head at each reciprocation thereof.

8. An apparatus for feeding seals of the character described to a bottle sealing device comprising a receptacle for the mass of seals, a chute communicating with said receptacle of a width to comfortably convey the seals only in endwise positions, a contracted annular entrance to said chute making the width of the chute at that point less than the height of the seals, said entrance having an annular side wall of zig-zag formation to permit edgewise positioned seals having flanges directed toward said zig-zag wall having a tumbling motion to pass the

said contracted entrance in tilted positions, and means for agitating said mass of seals.

9. A seal conveying chute having an entrance formed to admit flanged seals to the said chute in a predetermined direction by giving properly presented seals three consecutive oppositely inclined tilted positions in passing said entrance, said entrance comprising on one side a wall having three consecutively oppositely inclined sections, the union of the first two sections forming a contracted entrance of less width than the height of the seal for the purposes set forth.

In witness whereof I have hereunto set my hand, this 21st day of May, 1909.

CHARLES WINTER.
